UNITED STATES PATENT OFFICE

JOSEPH RAH, OF CHICAGO, ILLINOIS, ASSIGNOR TO G. & W. ELECTRIC SPECIALTY CO., OF CHICAGO, ILLINOIS, A CORPORATION OF ILLINOIS

CONDUCTOR DISCONNECTER ARRANGEMENT

Application filed May 20, 1925. Serial No. 31,539.

This invention relates to a conductor dis-
connecter arrangement.

One object of the invention is to provide a
simple and efficient conductor disconnector ar-
rangement in which the current conducting
parts are always covered to prevent injury
to one handling the disconnector whether or
not the electrical conducting parts or mem-
bers are in electrical engagement with each
other for completing or breaking a circuit.

Another object is to provide a device of the
class described in which the various parts co-
operate in an improved manner to make the
device entirely safe to handle and to adapt it
to meet all of the requirements under service
conditions.

These and other objects are accomplished
by means of the arrangement disclosed on the
accompanying sheet of drawings, in which

Fig. 1 is a vertical longitudinal sectional
view of a single conductor disconnector of the
pothead type embodying my invention;

Fig. 2 is a top plan view of the same device,
and

Fig. 3 is a detail sectional view showing the
movable electrical conductor moved out of
engagement with an associated electrical con-
ductor and into a position where the circuit is
broken and in which position said conductor
is covered and supported.

The various novel features of the invention
will be apparent from the following descrip-
tion and drawings and will be particularly
pointed out in the appended claims.

Referring to the figures of the drawings, it
will be noted that the invention as illustrated
in connection with a single conductor discon-
nector of the pothead type including an in-
sulating bushing 10, which preferably is ce-
mented at 11 to a support 12 having an at-
taching portion 13 by means of which the
whole device may be connected to and sup-
ported by any suitable support, such as a pole.
Supported in the insulating bushing 10 and

secured thereto is an electrical conductor or
contact member 14, to the upper end of which
is secured a cable lug 15 for connection to an
aerial cable. The electrical conductor 14 is
secured in the bushing 10 between a shoulder
16 in the bushing and the top of the bushing,

the conductor 14 having an enlarged portion
17 between which and the shoulder 13 a gasket
18 is mounted. Another gasket 19 is inter-
posed between the top of the insulating bush-
ing 10 and a nut or water shed cap 20, where-
by the conductor 14 is clamped in position
within the bushing 10. A lock nut 21 also en-
gages the threaded portion 22 of the conduc-
tor 14 for locking the latter in supported pos-
ition. The conductor 14 has a guide socket 23
for the reception of a combined split guide
plug and auxiliary or arcing contact 24, which
is formed at the upper end of a connector or
electrical conductor 25, the latter of which,
intermediate its ends, is provided with a col-
lar 26. This collar, when the parts are in their
normal connected position, is clamped be-
tween the lower part of conductor 14 and a
contact member 27, the latter of which is ce-
mented at 28 to an insulating handle 29. The
lower end of the conductor 14, which forms
a contact member, is externally threaded at
30 and cooperates with an internally threaded
portion 31 of the contact 27 so that said con-
tact members are interlocked with respect to
each other to prevent accidental disconnection
between same. The guide socket 23 and
guide pin 24 cooperate to guide said interlock-
ing portions into engagement with each other.
The connector 25, while it is supported in the
insulating handle 29, is free within said han-
dle to permit a relative rotation of the latter,
which is necessary in connecting and discon-
necting the threaded contact members men-
tioned. The lower end of the connector 25 is
connected to a cable lug 32, to which a ground
cable, for example, may be secured.

As shown in Fig. 1, the electric circuit is
completed from the cable lug 32 through
connector 25, collar 26, contact member 27,
contact member forming the lower portion
of conductor 14, to cable lug 15. If it is
desired to break the circuit, the insulating
handle 29 is rotated in the proper direction
for permitting withdrawal of the connector
25. During the first part of the separating
movement, the collar 26 of connector 25 is
withdrawn from the contact portion of con-
ductor 14, but no arcing takes place by virtue
of the fact that the circuit at such time is

not broken. The circuit is broken only when the contact plug 24 is drawn out of engagement with the conductor 14, and if there is any arcing, it takes place at the end of the contact plug 24 and a recessed portion 33 of conductor 14.

It will be appreciated that unless some special means is provided to cover and protect the connector 25 when it is withdrawn, the same would be left bare and be a serious hazard to one handling the device. Accordingly I have provided means which will cover the connector or conductor 25 not only when it is electrically connected to its associated parts, but also when it is disconnected from said parts. Such protecting means takes the form of a cylindrical insulating member or shield 34, the upper end of which has an inwardly-extending circular flange 35 which normally rests upon and is suspended from a collar 36 cemented or otherwise secured to the lower end of the insulating bushing 10. The lower end of the insulating shield 34 is provided with threaded ring 37, into which is screwed another ring 38, having connected thereto an internal collar 39, which is adapted to support the insulating handle 29 and the connector 25 when the latter has been drawn out of electrical association with the other conducting members. In this connection it will be noted that an annular member 40 is clamped between the contact member 27 and the upper end of the insulating handle 29 and is adapted to rest upon the collar 39, as shown in Fig. 3. In the position thus shown, the contact member 27, connector 25 and insulating handle 29 are supported by and suspended from the shield 34. By an inspection of Fig. 3, it is seen that the live parts are completely enclosed for protecting one handling the device.

While the insulating shield 34 normally is suspended from the bushing 10, said shield is telescopically arranged with respect to said bushing and may be moved upwardly with respect thereto to permit ready access to the insulating handle 29, which is used in connecting and disconnecting the electrical conductors. In this way the electrical conductors not only are completely housed at all times, whether connected or disconnected, but the parts are so arranged to make connection and disconnection a simple matter.

I claim:

1. In a device of the class described, the combination of a plurality of electrical conductors adapted to be electrically connected and disconnected, two protecting members for covering said conductors when connected, and a third protecting member associated with both of said conductors for covering at least one of said conductors when said conductors are disconnected.

2. In a device of the class described, the

combination of a plurality of electrical conductors adapted to be electrically connected and disconnected, two protecting members for covering said conductors when connected, and an associated telescopically arranged protecting member for covering one of said conductors and movable with respect to said conductors when it is moved out of electrical association with another of said conductors.

3. In a device of the class described, the combination of a plurality of conductors adapted to be electrically connected and disconnected, protecting means for covering said conductors when connected, and associated protecting means suspended from the first protecting means and associated with the second protecting means for covering one of said conductors when it is electrically disconnected from another of said conductors.

4. In a device of the class described, the combination of a plurality of electrical conductors adapted to be electrically connected and disconnected, an insulating bushing enclosing one of said conductors, and another insulating member movable with respect to and depending from said insulating bushing for enclosing another of said conductors when said conductors are disconnected.

5. In a device of the class described, the combination of a plurality of electrical conductors adapted to be electrically connected and disconnected, a bushing enclosing one of said conductors and having a supporting collar, and another insulating member suspended from said supporting collar and adapted to enclose another of said conductor when said conductors are electrically disconnected and said last named conductor is removed from said first named bushing.

6. In a device of the class described, the combination of a plurality of electrical conductors adapted to be electrically connected and disconnected, a bushing enclosing one of said conductors and having a supporting collar, another insulating member suspended from said supporting collar and adapted to enclose another of said conductors when said conductors are electrically disconnected and said last named conductor is removed from said first named bushing, and means whereby said second insulating member supports one of said conductors in a given position.

7. In a device of the class described, the combination of a stationary electrical conductor and a movable conductor adapted to be electrically connected and disconnected, a bushing enclosing said stationary conductor, and associated protecting means comprising two telescopically arranged members for covering the movable conductor and associated with the stationary conductor when said conductors are electrically connected and disconnected.

8. In a device of the class described, the

combination of a stationary electrical conductor and a movable conductor adapted to be electrically connected and disconnected, a bushing enclosing said stationary conductor, and an insulating member suspended from said bushing for covering said movable conductor when said conductors are electrically disconnected to remove said movable conductor to a position remote from said first named bushing.

9. In a device of the class described, the combination of a stationary electrical conductor and a movable conductor adapted to be electrically connected and disconnected, an insulating bushing enclosing said stationary conductor, and an insulating member suspended from said bushing for covering said movable conductor when said conductors are electrically disconnected, said movable conductor being supported by said insulating member when said conductors are disconnected at a position remote from said first named bushing.

10. In a device of the class described, the combination of two electrical conductors adapted to be electrically connected and disconnected, an insulating bushing enclosing one of said conductors, an insulating handle mounted on another of said conductors and cooperating with said bushing to cover said conductors when they are electrically connected, and an additional protecting member associated with said conductor for covering one of said conductors when said conductors are disconnected.

11. In a device of the class described, the combination of two electrical conductors adapted to be electrically connected and disconnected, an insulating bushing enclosing one of said conductors, an insulating handle mounted on another of said conductors and cooperating with said bushing to cover said conductors when they are electrically connected, and an insulating member suspended from said bushing and adapted to house one of said conductors when said conductors are electrically disconnected.

12. In a device of the class described, the combination of two electrical conductors adapted to be electrically connected and disconnected, an insulating bushing enclosing one of said conductors, an insulating handle mounted on another of said conductors and cooperating with said bushing to cover said conductors when they are electrically connected, an insulating member suspended from said bushing and adapted to house one of said conductors when said conductors are electrically disconnected, and means whereby said insulating handle and one of said conductors are supported by and suspended from said insulating member when said conductors are disconnected.

13. In a device of the character described, the combination of conductors, one of said

conductors being threaded, a threaded member associated with the other of said conductors for engagement with the threaded conductor to thereby effect a connection therewith, a plurality of insulating members to insulate the connection, one of said members providing a handle to impart threading movement thereto, and means associated with said insulating members to protectingly support the connectors in disconnected position.

14. In a device of the character described, the combination of a conductor, an insulating bushing therefor, a conductor adapted to have electrical connection with said first named conductor, means cooperating with said conductors for maintaining said conductors in electrical connection, a bushing for said second named conductor for operating said first named means, and means carried by said first named bushing for supporting said second named bushing when said conductors are disconnected.

15. In a device of the character described, the combination of a conductor, an insulating bushing therefor, a conductor adapted to have electrical connection with said first named conductor, means cooperating with said conductors for maintaining said conductors in electrical connection, an insulating bushing for said second named conductor for operating said first named means, and an insulating sleeve carried by said first named bushing for supporting said second named bushing when said conductors are disconnected.

Signed at Chicago, Illinois, this 18th day of May, 1925.

JOSEPH RAH.
